(57) CLAIM

The ornamental design for a parasol base, as shown and described.

DESCRIPTION

FIG. 1 is a front view of a parasol base showing my new design;

FIG. 2 is a rear view thereof;

FIG. 3 is a right side view thereof;

FIG. 4 is a left side view thereof;

FIG. 5 is a top view thereof;

FIG. 6 is a bottom view thereof; and,

FIG. 7 is a top-front-right view thereof.

The broken lines of the drawings show portions of the parasol base that form no part of the claimed design.
